UNITED STATES PATENT OFFICE.

JOHN P. ARNDT, OF MILWAUKEE, WISCONSIN.

CIRCUIT BREAKER.

1,403,373.

Specification of Letters Patent. Patented Jan. 10, 1922.

Application filed October 24, 1919. Serial No. 333,002.

To all whom it may concern:

Be it known that I, JOHN P. ARNDT, a citizen of the United States, residing at Milwaukee, in the county of Milwaukee and State of Wisconsin, have invented new and useful Improvements in Circuit Breakers, of which the following is a specification.

This invention relates to circuit breakers.

One of the objects of the invention is to provide an improved circuit breaker for use with contact slips.

Another object is to provide an improved circuit breaker which may be easily and quickly assembled.

Another object is to provide an improved circuit breaker the contacts of which when damaged by arcing may be readily replaced.

Another object is to provide an improved circuit breaker wherein the duration of the arcing between the contacts thereof is reduced to a minimum.

Another object is to provide an improved circuit breaker which may be either automatically or manually tripped.

Another object is to provide an enclosed circuit breaker which is readily removable from its enclosing casing.

Other objects and advantages will appear from the specification and claims.

One embodiment of the invention is shown in the accompanying drawings in which—

Figure 1 is a side elevation of a circuit breaker, with the tubular support in section showing the circuit breaker in open condition.

Figure 2 is a side elevation of the circuit breaker of Figure 1 showing the circuit breaker in closed condition.

Figure 3 is a vertical section through the circuit breaker shown in Figure 1.

Figure 4 is a sectional view on line 4—4 of Figure 3.

Figure 5 is a sectional view on line 5—5 of Figure 3.

Figure 6 is a sectional view on line 6—6 of Figure 3.

Figure 7 is a sectional view on line 7—7 of Figure 3.

Figure 8 is a perspective of the upper terminal and associated stationary main and auxiliary contacts of the circuit breaker.

Figure 9 is a perspective of the lower terminal of the circuit breaker.

Figure 10 is a side elevation of the tubular support with the lower terminal removed

to show the means for locking the upper and lower sections of the tubular support together.

Figure 11 is a perspective of the latch and dashpot mounted upon a supporting frame, and the armature and lever for releasing the latch.

In general, the illustrated circuit breaker comprises a tubular support carrying two circuit terminals for cooperation with contact clips to hold the support in place and complete the circuit and a circuit interrupter within the support.

The circuit interrupter within the tubular support has a pair of main contacts through which the circuit is primarily closed, and a pair of auxiliary or arcing contacts between which the circuit is finally opened. The main and auxiliary contacts are normally maintained in closed relation but are adapted to be opened upon the occurrence of predetermined abnormal conditions. When the contacts are opened, a blast of air is provided between the auxiliary contacts to aid in preventing or interrupting any arc which may tend to form or persist therebetween.

Referring to Figures 1, 2 and 3 of the drawings the upper section 1 of the tubular support of suitable insulating material, such as bakelite carries two circuit terminals 3 and 4 of copper positioned near opposite ends of the section 1.

The terminal 3 extends through aligned slots in the section 1 and a ferrule 5 provided thereon. The inner end of the ferrule 5 is crimped into a groove in the section 1 for securing the ferrule thereto and for forming a tight fit therebetween. The inner end of the terminal 3 is formed into a cylindrical tube 7 which serves as the stationary main contact. A cap 6 removably clamped to the ferrule 5 is provided with a lug 60 which fits in the upper end of the contact tube 7 and cooperates with the slotted section 1 to hold the terminal 3 and the tubular contact 7 in position.

The stationary auxiliary contact of the circuit breaker is an annular disk 8 of copper having a projection 9 struck up therefrom to engage a slot in the main contact tube 7 for holding the annular disk against the lower edge of the main contact tube 7. The opposite margin of the annular disk is brazed or soldered to a shoulder 10 on the blade terminal 3. A barrier ring 11 of in-

sulating material is held in spaced relation to the annular disk 8 by means of screws 12.

The inner end of the lower terminal 4 is provided with two laterally extending arcuate ears 13 and 14 by which the terminal is mounted on a ferrule 15 on the lower end of the section 1 of the tubular support. The upper end of the ferrule 15 is crimped into a groove in the support 1 for securing the ferrule thereto and for forming a tight fit therebetween. A guide finger 19 is provided for positioning the terminal 4 in the contact clips between which it is connected.

Two downwardly extending lugs 16 and 17 formed on the lower edge of the blade terminal 4 form a bracket for supporting the solenoid coil 18 the lower end of which is seated in and connected with the bracket. A copper tube 20 mounted in the top of a brass piston 21 forms the movable main contact of the circuit breaker. A brass collar 22 surrounding the tube 20 and insulated therefrom by an insulating sleeve 23 to which it is secured forms the movable auxiliary contact of the circuit breaker. A compression spring 24 which is secured at its lower end to the piston 21 carries at its upper end the auxiliary contact 22. The auxiliary contact 22 is therefore movable with respect to the main contact 20.

The operating solenoid 18 of the circuit breaker has a brass tube 30 within which a tubular armature 31 reciprocates. An insulating sleeve 32 separates the solenoid 18 and the brass tube 30. The lower end of the brass tube 30 passes through an opening in and is secured to the cross head 33 of a bracket supporting the latch mechanism of the circuit breaker. An annular insulating disk 34 insulates the solenoid winding 18 from the cross head 33. An annular disk 35 provided with a slot through which extends the upper terminal of the solenoid coil 18 is seated on top of the brass tube 30 and is clamped thereto by the shoulder on a steel bushing 36 extending through the opening in the disk 35 and having screw threaded engagement with the inside of the brass tube 30.

For elevating the piston 21 and the contacts carried thereby a piston rod 37 extending through the bore of the steel bushing 36 is connected with the lower end of the contact tube 20 by means of an arbor 38.

This arbor 38, as will more fully hereinafter appear, serves as an air intake for the contact tube 20. Clamped between the upper end of the arbor 38 and the end of the piston 21 is an annular contact disk 39 connected with the upper terminal of the solenoid coil by a flexible cable 40.

The movable auxiliary contact 22 is connected with the piston 21 by a flexible cable 41. A main spring 42 is connected at its upper end with the arbor 38 and at its lower

end with the steel bushing 36. This main spring normally tends to separate the main contacts.

The cross head 33 of the bracket supporting the latch mechanism has two downwardly extending legs 43 and 44 carrying between the lower extremities thereof a base plate 45. A latch 46 pivoted between two downwardly extending lugs 47 and 48 is provided with a detent 49 for engaging a shoulder 50 formed on the piston rod 37 adjacent the fibre knob 51.

The tubular armature 31 carries at its lower end a plate 52. This plate 52 is slotted to provide a tongue 53 for engaging the upper end of a link 54 connected with the outer end of the latch 46.

In order that the circuit breaker may not be opened upon each and every surge of excess current through the solenoid coil 18, but only upon excess current passing therethrough for a predetermined time, the upward movement of the tubular armature is retarded by a dashpot having an adjustable cylinder 55 supported by the plate 45 and a piston 56 connected with the plate 52.

The latch 46 and dashpot and the supporting bracket 43 therefor which extend below the lower end of section 1 of the tubular support are enclosed by the lower section 2 of the tubular support. The upper end of this lower section 2 fitting within the ferrule 15 is provided with an L-shaped slot 57 which allows the lower section to be locked in position by the lower end of the solenoid coil 18 which extends through a slot in the ferrule 15.

The bottom of the section 2 is enclosed by an insulating disk 58 having an opening through which the rod 37 extends. The upper end of a push rod 59 carried by the insulating disk 58 may be manually moved into engagement with the lower end of the link 54 for operating the latch 46.

The illustrated circuit breaker may be connected in circuit by inserting the terminals 3 and 4 between contact clips. This connection of the circuit breaker in circuit requires but a direct thrust movement, whereby the circuit breaker may be easily and quickly connected to and disconnected from the contact clips. The guide finger 19 provided on the lower terminal 4 not only serves to guide and position the circuit breaker in the contact clips, but prevents the circuit breaker from being jarred therefrom upon the opening of the contacts of the circuit breaker due to the passage of excess current or when the latch is manually released.

To close the contacts of the circuit breaker, the support thereof is held stationary while the rod 37 is pushed up until the detent 49 of the latch 46 engages the shoulder 50 thereby holding the rod in ele-

vated position. As the rod rises the piston 21 and the parts carried thereby are moved upward against the action of the main spring 42 which is thereby put under tension. During the upward movement of the moving parts of the circuit breaker, the moving auxiliary contact 22 engages the stationary auxiliary contact 8 whereupon the auxiliary compression spring 24 becomes active. As the upward movement continues this spring 24 is compressed, and the movable main contact 20 moves through the insulating bushing 23 and into the stationary tubular main contact 7 with which it contacts. Figure 2 shows the circuit breaker in closed condition with the main spring 42 under tension and with the auxiliary spring 24 under compression.

The circuit through the circuit breaker 20 may be traced from the terminal 4, through the solenoid coil 18, cable conductor 40, contact plate 39, piston 21, tubular contacts 20 and 7 and the terminal 3.

When excess current traverses the solenoid coil 18, the tubular armature 31 is drawn upwardly within the brass tube 30 carrying with it the plate 52. The dashpot retards the movement of the armature and plate, so that if the excess current is but a surge of short duration the tongue 53 does not engage the link 54. However if excess current flows for a predetermined length of time, the armature 44 travels far enough to permit the tongue 53 to engage and elevate the link 54. The latch 46 is thereby moved about its pivot point causing the detent 49 to move out of engagement with the shoulder 50 for releasing the rod 37. As soon as the rod 37 is released, the main and auxiliary springs 42 and 24 begin to move the contact tube 20 out of engagement with the contact 7. During this action the spring 42 is pulling down on the piston 21 and the spring 24 is pushing down thereon. Due to the action of the auxiliary spring 24, the auxiliary contact 22 is maintained in engagement with the auxiliary contact 8 until after the disengagement of the main contacts 20 and 7, so that the main contacts first disengage and then the auxiliary contacts.

This piston 21 compresses the air in the tubular support when the contacts are separated to provide a blast of air which is blown against and between the auxiliary contacts to prevent the formation of an arc or to quench an arc which may tend to persist. By mounting the stationary auxiliary disk contact 8 against the bottom of the stationary main tubular contact 7 and by providing the ring barrier 11 in spaced relation to the auxiliary disk contact 8, the blast of air is directed against and between the auxiliary contacts. Destructive prolongation of the arc is thus prevented and the contacts are preserved.

By the construction employed, it will be seen that the stationary main and auxiliary contacts and the upper terminal are removable as a unit from the tubular support. This unit, as shown in Fig. 8, may be easily 70 and quickly removed when it is desired to inspect the contacts. Furthermore by mounting these contacts and this terminal as a unit, such units may be assembled and carried in stock, and when making repairs. 75 it is only necessary to remove the damaged unit and replace it with a perfect one.

It will also be seen that the lower terminal supports the solenoid, the armature, the movable contacts and the latch and dashpot. Therefore this terminal and the various parts of the circuit breaker supported thereby may be removed as a unit from the tubular support.

The circuit breaker is provided with 85 means for manually tripping it, so that when it is desired to inspect the circuit breaker, it may be tripped before removing it from the circuit. By tripping the circuit breaker before it is removed from 90 the circuit the circuit terminals of the circuit breaker and the contact clips engaged by the circuit terminals are protected.

The stationary auxiliary contact is removably carried by the upper terminal, so that 95 when an auxiliary contact becomes damaged it may be easily and quickly removed and replaced by a perfect one.

Obviously other structures may be devised which will embody the invention herein set forth. The drawings and description thereof are therefore to be considered merely in an illustrative and not in a limiting sense.

What is claimed is:

1. A circuit breaker comprising a pair of relatively movable contacts, a spring tending to separate the contacts, a latch for holding the contacts in closed relation, an electromagnet responsive upon the occurrence of 110 abnormal conditions to release the latch to allow the spring to open the contacts, and time controlled means for delaying the release of the latch.

2. A circuit breaker for use with contact clips, comprising a tubular support, a pair of circuit terminals carried thereby for cooperation with the clips to hold the support in place and complete the circuit, a pair of contacts within the support for completing 115 the circuit between the terminals, one contact being carried by one terminal and the other contact by the other terminal, a spring tending to separate the contacts, a latch carried by one terminal and holding the contacts in closed relation, an electromagnet within the support carried by one terminal and being responsive upon the passage of excess current to release the latch to allow the 120 spring to open the contacts, and time controlled means for delaying the release of the latch.

trolled means carried by the electro-magnet and cooperating therewith to delay the release of the latch.

3. A circuit breaker for use with contact clips, comprising a tubular support, a pair of circuit terminals carried thereby for co-operation with the clips to hold the support in place and complete the circuit, a main contact formed integral with one terminal, a removable auxiliary contact carried thereby, movable main and auxiliary contacts within the support, a latch for holding the main contacts in closed relation, a spring tending to separate the main contacts, an electro-magnet within the support and responsive to the passage of excess current to release the latch to allow the spring to open the main contacts, and means controlled by the electro-magnet for causing the auxiliary contacts to separate after the opening of the main contacts.

4. A circuit breaker comprising a pair of relatively movable main contacts having sliding engagement, an electro-magnet for causing the separation thereof upon the passage of excess current, auxiliary contacts also controlled by the electro-magnet to open subsequently to the separation of the main contacts, said auxiliary contacts having abutting engagement, and means controlled by the electro-magnet for producing a blast of

air against and between the auxiliary contacts, and a barrier cooperating with the auxiliary contacts to confine the blast of air between the auxiliary contacts.

5. A circuit breaker for use with contact clips, comprising a tubular support, a pair of circuit terminals carried thereby for co-operation with the clips to hold the support in place and complete the circuit, and an electromagnetically controlled circuit interrupter within the support, said interrupter including relatively movable main contacts and relatively movable auxiliary contacts, one of the auxiliary contacts being removable supported by one of the terminals.

6. A circuit breaker comprising a pair of circuit terminals, a pair of main contacts in circuit with the terminals, an electro-magnet responsive upon the passage of excess current to open the main contacts, and a pair of auxiliary contacts also controlled by the electro-magnet to open after the separation of the main contacts, one of the auxiliary contacts being removably carried by one of the circuit terminals, means for manually tripping the circuit breaker to open the main contacts.

In witness whereof, I have hereunto subscribed my name.

JOHN P. ARNDT.
